UNITED STATES PATENT OFFICE.

HERMAN TAPPAN, OF NEW YORK, N. Y.

DESIGN FOR A BOTTLE-CAP.

SPECIFICATION forming part of **Design No. 28,636, dated May 17, 1898.**

Application filed April 11, 1898. Serial No. 677,238. Term of patent 7 years.

To all whom it may concern:

Be it known that I, HERMAN TAPPAN, of the city of New York, (borough of Manhattan,) in the county and State of New York, have 5 invented and produced a new and original Design for a Bottle-Cap, of which the following is a full, clear, and exact specification.

Reference is to be had to the accompanying drawing, forming a part of this specification, 10 in which the figure is a perspective view of a bottle-cap showing my design.

The leading feature of my design consists in the spiral rib A, forming the lower or base

portion of the cap, the rib terminating at the lower end of a cylinder B, crowned by a head 15 C, the side of which bulges out, the top thereof being arched.

A minor feature consists in the very slight taper given to the sides of the cylinder B.

I claim—

20 The design for a bottle-cap, as herein shown and described.

HERMAN TAPPAN.
